Vincent J. Burnelli INVENTOR.

BY *Frederick S. Barker*

ATTORNEY.

UNITED STATES PATENT OFFICE.

VINCENT J. BURNELLI, OF NEW YORK, N. Y.

AIRPLANE.

Application filed May 7, 1927. Serial No. 189,527.

This invention relates to a novel form of retractable chassis for airplanes and my improvements are directed particularly to a retractable chassis arranged and adapted for use in conjunction with a fuselage of considerable width, such for example as the Remington-Burnelli type of large carrying capacity airplane, having its fuselage throughout of aerofoil contour to comprise a central supporting unit.

Briefly expressed my invention consists in providing a hinged pendent wheel-hanger at each side of the fuselage in such manner that the hanger with the wheel may be swung toward the under surface of the fuselage, wherein a pocket is provided for the reception of the wheel to lie horizontally embedded therein. Since the opposite wheels are movable inwardly and upwardly to both find lodgment in the same horizontal plane in embedded relation at the bottom of the fuselage, obviously the fuselage must have such width as is provided only by the broad, aerofoil contoured fuselage of the Remington-Burnelli type of airplane.

As means of effecting retraction and return to normal position of the wheels there extends an angled bracket from the inner hub of each wheel, each bracket having a gear mounted at its free end in engagement with an arcuate rack that is extended through the fuselage, a motor geared to said pinion serving to rotate the latter and thereby cause it to travel along the rack, to both draw the wheel into its retracted position and to return it to its pendent operative position.

Other features and advantages of my invention will hereinafter appear.

40 In the drawings:

Figure 1 is a front elevation of an airplane having a fuselage of aerofoil contour equipped with my improved retractible chassis.

45 Fig. 2 is a side elevation thereof, only the forward portion of the airplane appearing in this view.

Fig. 3 is a partial top plan view of the same.

50 Fig. 4 is an enlarged partial front view in section showing one of the retractible wheels with its supporting and operating gear, the wheel being in normal position.

55 Fig. 5 is a similar view showing the wheel and gear retracted and housed, and

Fig. 6 is a detail of the motor and gear train.

In the views let 1 indicate a fuselage of aerofoil contour, having the nose portion 2, in which the engines 3, 3 are housed and disposed one at each side within said nose portion, the engine shafts projecting forwardly and respectively carrying the propellers 4, 4 that operate in the same vertical plane.

The wheels 5, 5 of my improved retractible chassis are, as will be observed, spaced apart the full width of the fuselage so as to afford a broad gauge trackway. Said wheels are connected to the sides of the fuselage respectively by hangers 6, 6 that respectively engage the outer hubs 7, 7 of the wheels, and at their upper ends are hinged, as at 8, 8 to laterally abutting lugs or fittings 9, 9 secured to the fuselage sides. The hangers 6, 6 by reason of the hinged connection are adapted to retract into a horizontal position against the bottom surface of the fuselage, and said fuselage is provided with recesses or pockets 10, 10 each suited in its area and depth for the reception and housing of one of the wheels 5.

The wheels 5, 5 also are each provided with a bracket or inclined arm 11 that is rigidly connected to the inner hub 12 and extends to the bottom of the fuselage when the wheel is in service. The upper or free end of each bracket or arm 11 is provided with a pivotal gear 13 that engages in an arcuate rack 14 which is secured within the fuselage and extends over one of the recesses or pockets 10, said rack serving as a guide for the gear 13 and arm 11 in the retraction of a wheel into its pocket 10, and in the outward movement of the wheel back to its service position.

As means for moving the wheels to and from their retracted positions I provide motors 15 which are respectively carried by mounts 16 secured upon the free ends of the arms 11.

In the example of Fig. 6 a motor 15 is shown as having a rotor shaft 17 carrying a gear 18 which drives the gear 13 through an intermediary idler 19. The source of electrical energy for operating the motor is not shown, but will be understood as being available on the airplane.

The arcuate racks 14, 14 are necessarily divergent in their relative arrangement be-

cause the wheels in their retractile operation swing toward each other and in consequence the arms 11, 11, in the same action, have to swing outwardly, these operations obviously being reversed when the wheels are swung into their service positions.

For sturdiness of support, additional hangers 20, 20, hinged to the fuselage at 21, 21, extend angularly between the wheel 10 outer hubs 7, 7 and a rearward portion of the fuselage.

Variations within the spirit and scope of my invention are equally comprehended by the foregoing disclosure.

15 I claim:

1. The combination with an airplane having a fuselage of a chassis therefor comprising wheels disposed at opposite sides beneath said fuselage, pendent hangers hinged 20 one at each side of the fuselage and having rigid connection with said wheels, at their outer hubs, inclined arms having rigid connection with the inner hubs of the wheels respectively, said arms converging toward 25 the fuselage bottom, gears carried by said arms at their free ends, arcuate racks en-

gaging said gears and extended divergently upward through said fuselage, and means for moving said gears along said racks to retract said chassis and thereby move said 30 wheels into a horizontal plane at the bottom of said fuselage.

2. The combination with an airplane having a fuselage provided with a pair of transversely disposed recesses in its bottom, of a 35 chassis comprising wheels disposed at opposite sides beneath said fuselage, pendent hangers hinged one at each side of the fuselage and having rigid connection with said 40 wheels at their outer hubs, inclined arms having rigid connection with the inner hubs of the wheels respectively, said arms converging toward the fuselage bottom, gears carried by said arms at their free ends, 45 arcuate racks engaging said gears and extended divergently upward through said fuselage, and means for moving said gears along said racks to retract said chassis and thereby move said wheels respectively into 50 said recesses in the fuselage bottom.

New York, March 6th, 1927.

VINCENT J. BURNELLI.
